Primary Examiner — Philip S Hyder(74) *Attorney, Agent, or Firm* — FisherBroyles, LLP;
Craig W. Mueller(57) **CLAIM**

The ornamental design for a knife, as shown and described.

DESCRIPTION

FIG. 1 is a perspective view of the knife;
FIG. 2 is a front elevation view thereof;
FIG. 3 is a rear elevation view thereof;
FIG. 4 is a left elevation view thereof;
FIG. 5 is a right elevation view thereof;
FIG. 6 is a top plan view thereof;
FIG. 7 is a bottom plan view thereof;
FIG. 8 is a perspective view thereof, wherein a blade has
been removed from a blade carrier;
FIG. 9 is a perspective view of the knife shown in a folded
configuration;
FIG. 10 is a front elevation view thereof;
FIG. 11 is a rear elevation view thereof;
FIG. 12 is a left elevation view thereof;
FIG. 13 is a right elevation view thereof;
FIG. 14 is a top plan view thereof; and,
FIG. 15 is a bottom plan view thereof.
The broken lines are directed to portions of the knife that
form no part of the claim.
